UNITED STATES PATENT OFFICE.

GIUSEPPE GAYS, OF LOS ANGELES, CALIFORNIA.

PROPELLER.

1,080,964.

Specification of Letters Patent.

Patented Dec. 9, 1913.

Application filed November 13, 1912. Serial No. 731,118.

To all whom it may concern:

Be it known that I, GIUSEPPE GAYS, a subject of the King of Italy, who have declared my intention of becoming a citizen 5 of the United States, residing at Los Angeles, county of Los Angeles, and State of California, have invented new and useful Improvements in Propellers, of which the following is a specification.

10 This invention relates to improvements in propellers for aquatic use, more particularly to that class and description as shown and described in my prior United States Letters Patent, Number 958,108, issued to me

15 May 17, 1910.

In the further adaptation and utilization 20 of propellers for vessel-propulsion, which embody means for producing relatively increased degrees of operative thrust upon the resisting mass of water, wherein the water is set in motion by the revolutions of the propeller to the end that the water is utilized as a bearing agency for the propeller through a constantly increasing range of 25 propulsive activity, from the point at which the forward portion of the propeller first engages a given mass of water to the point at which such mass of water is finally thrown or discharged from the propeller 30 and which embody the means for providing a propeller having a series of members or blades of varied thrust areas, each of which members or blades have their edges overlapping with relation to each other. It is found with respect to the practice, that the 35 elimination of propulsive vibration, that is, reducing said vibration to a minimum is rather difficult. In order to reduce the vibration resultant of the propulsive revolution it is found that each of the members 40 or blades of the propeller must necessarily be of equal increasing operative dimensions of thrust producing areas and that a given mass of water must be in equal resistance 45 to each of said members or blades in the thrust producing propulsion thereof, as the propeller is rotated in said given mass of water.

In this invention I propose to employ 50 members or blades on the propelling shaft, each of which are so constructed as to conform to the lines of a spiral screw of con-

stantly increasing thrust area with respect to the forward propulsion thereof; each of said spiral members or blades having their 55 starting points on the shaft, one slightly leading the other and each having its concave water resistance surface slightly shallower than that of the member or blade following, so that an equal mass of water is 60 moved over the resisting surfaces of each member or blade in exactly the same duration of time, that is, from the time a given mass of water is engaged by one of said members or blades to the time said mass is 65 finally discharged therefrom, is equal with respect to the engagement of a like amount of water in, or by one of the other members or blades. The backs or rearward faces of 70 the members or blades are of convex formation, of such irregular curvature that the "dead" water not engaged by the revolution of the propeller is in minimum resistance thereto and the action of the water in motion in the spiral between any two of 75 such members or blades on the back of the leading member or blade is in minimum resistance to said water in motion, so that the propulsive activity of the propeller is not retarded to any great degree by the displacement of the water in motion in the spirals, nor by the "dead" water in front of the 80 propeller, which is the back of the members or blades.

An object of the invention is the provision 85 of a propeller of the above general character which is comparatively simple and inexpensive in construction, embodying positiveness in operation and that is superior in point of relative efficiency and serviceability.

Another object of the invention is primarily the provision of an improved propeller of the character stated, in which the vibration is substantially null, and in which 95 the resultant minimum vibration of the revoluble composite parts is uniform with relation to the centrifugal force or propulsive activity and the equal thrust areas of each of the composite parts.

A further object of the invention is the provision of an improved propeller of the stated character in which each of the members or blades thereof is provided with a

- circular rib of increasing dimensions of projection on the propulsive thrust producing or water resisting surfaces; such circular rib being circumferential of the shaft and 5 so arranged on said surfaces as to retard the accelerated momentum of the water being deflected over said surfaces, which is the means of lengthening the duration of time in which a given mass of water would otherwise have been discharged from the ends 10 of said members or blades, thereby greatly increasing the propulsive thrust of the propeller, which results in a considerable saving of fuel consumption.
- 15 A still further object of the invention is to provide members or blades of spiral formation of the character described, which take off from the propelling shaft at different stations longitudinally thereof, so that one 20 leads the other and each overlaps one and underlaps another of said blades; each of said stations being equally spaced from the other circumferentially of said shaft.

In practice it is found that my improved 25 propeller picks up the "dead" water and sets it in motion on the water resisting thrust producing surfaces so that the direction of movement of said water is toward the axial center of the propeller there- 30 by increasing its efficiency of thrust productiveness.

With the above general objects in view the invention further consists in the novel provision, formation, construction, organization, combination and relative arrangement of parts, members and features, all as hereinafter described, shown in the drawings and finally pointed out in the claims.

In the drawings: Figure 1 is a side elevation exteriorly showing a propeller constructed in accordance with the invention, the dotted lines denoting a portion of a vessel, to which the invention is connected; Fig. 2 is an end view of the parts shown in 45 Fig. 1, looking in the direction of the appended arrow; Fig. 3 is a view of one of the members or blades as it would appear if removed from the shaft; and Figs. 4 and 5 are each detail views taken on the lines 50 X^4-X^4 and X^5-X^5 respectively of Figs. 2 and 3, showing the approximate cross-sectional formation of the members or blades shown in the several views.

Like characters of reference designate like 55 parts throughout the several views of the drawings.

Referring with particularity to the drawings, the members or blades of the propeller embodying the invention are designated by 60 the characters A, B and C respectively, in the present instance there being three of such members or blades, each being of spiral screw formation and extending longitudinally of the shaft D which latter represents

the customary power shaft extending from 65 the motor or other propulsive means for rotating the shaft and thereby said members or blades.

a , b and c represent the points on the shaft D where the spiral members or blades 70 A, B and C start on the circumference thereof, the member or blade A being first and starting as at a and extending rearwardly of said shaft, the member or blade B starting as at b which is spaced a predetermined 75 distance to the rear of the point a and 120 degrees therefrom on the circumference of said shaft, and the member or blade C starting as at c , which is to the rear of the 80 point b and 120 degrees therefrom on the circumference of said shaft; the member or blade A overlapping the member or blade B and underlapping the member or blade C, the member or blade B overlapping the member or blade C and underlapping the member or blade A, and the member or blade C overlapping the member or blade A and underlapping the member or blade B. This arrangement spaces the points a , b and c one-third of the shaft circumference 90 or 120 degrees apart on the periphery of said shaft and one slightly leading the other longitudinally of said shaft. The rearward ends d , e and f of the members or blades 95 A, B and C, are in true vertical alinement with each other, so it will be seen that the member or blade A is the longer spiral, the member or blade B being the next longest and the member or blade C being the shorter of the three and owing to this difference of 100 length, it is necessary that the concave curvature or water resisting surface g of the member or blade A be of shallower depth than the depth of the surface h of the member or blade B and as the member or blade 105 C is the shorter, it must necessarily be of the greatest depth of the like concave surface i . The outer edges j , k and l of said members or blades A, B and C conform to a helix from the points a , b and c as they recede radially from said shaft as shown in Figs. 1 and 2 of the drawings; the depth of the spiral screw from the helical edge to the shaft at any given point being equal with relation to each of the other spiral members or blades. The backs or rearward faces m , n and o , of the members or blades 110 A, B and C are of convex curvature approximately the opposite of the concave surfaces g , h and i so as to be in minimum re- 115 sistance to the "dead" water as it is picked up by the propeller and as it is set in motion and accelerated over the concave water resisting surfaces g , h and i in the spiral between any two of said members or blades. 120 The circular ribs E, F and G are provided on the surfaces g , h and i , extending common to an equal radius of the center of

the shaft, and of constantly increasing dimensions of projection outwardly from said surfaces, for the purpose of retarding the accelerated water being deflected over said surfaces in the spiral intermediate the overlapping members or blades, which is the spaces between said members or blades, thereby greatly increasing the forward thrust or propulsive activity by lengthening the duration of time in which a given mass of water would otherwise have been discharged from the ends *d*, *e* and *f* of said members or blades.

It is manifest from the foregoing that the inertia of the water engaged by the members or blades of the propeller is utilized for greater thrust productiveness. The overlapping and underlapping features of the members or blades impart an even motion, with an absolute minimum vibration in the operation of the propeller.

The invention may be utilized with two members or blades instead of three, as herein shown, wherein each member or blade overlaps and underlaps the other of such members or blades.

In practice it is found that the three member or blade type is especially adaptable for oceanic service in the vicinity of the coast line or off and about the reefs, shoals or small islands, where there is various vegetable growths in the water usually in the form of kelp, but in some instances in the form of so called "marine gardens," consisting of many various and different kinds of such vegetation. The formation of blades is such that when growths of the above character are encountered the revolution thereof has a natural or inherent tendency to cast most of said growth without the radius of revolution, while a small per cent. is cut into small pieces, as it is taken into the spiral with the "dead" water.

I do not desire to be understood as limiting myself to the specific provision, formation, construction, organization, combination, and relative arrangement of parts, members and features as herein shown and described; but reserve the right to vary the same in adapting the improvements to varying conditions of use, without departing from the spirit of or sacrificing any of the advantages of the terms of the following claims.

Having thus fully described my invention, what I claim as new therein, and desire to secure by Letters Patent, is:—

1. A propeller comprising a plurality of blades in which the revoluble effective propelling surface conforms to a spiral, each blade overlapping one and underlapping another of such blades; said spiral blades be-

ing of different lengths of spiral and of different depths of concave curvature; the lengths of spirals and the depths of the concave surfaces being such that each blade exerts equal propulsive thrust from a given mass of water in an equal duration of time; a shaft on which the propeller is mounted; each of said blades having its edge of helical conformation and being of equal distance from the shaft at a given point as it recedes from said shaft; and a circular rib on each of said water resisting surfaces for retarding the flow of water in the spaces between the blades, substantially as described.

2. An improved propeller having a plurality of blades, each of which overlaps one and underlaps another of such blades; and a circular rib of varying dimensions of projection on the thrust producing water resisting surfaces of each of such blades, to retard the deflecting water in motion over said surfaces, said ribs being circumferential of the center of the shaft, substantially as described.

3. An improved propeller having three blades, each of which overlaps one and underlaps another of such blades; a propelling shaft on which the blades are fastened; and a circular rib of varying dimensions of projection on the thrust producing water resisting surfaces of each of such blades, to retard the flow of the water over said surfaces; said ribs extending circumferential of the axial center of said propeller, substantially as described.

4. An improved propeller having three blades, each of which overlaps one and underlaps another of such blades; a propelling shaft carrying the blades; and a circular rib of varying dimensions of projection on the thrust producing water resisting surfaces of such blades, to retard the flow of a given mass of water over said surfaces; said blades being of spiral conformation longitudinally of the shaft, and each conforming to a helix of equal depth of the spiral screw, as at a given point it recedes from said shaft; said blades each being of concave curvature of slightly varying degrees, so that a given mass of water is productive of equal thrust in each blade in an equal duration of time, substantially as described.

5. An improved propeller having three blades each of which overlaps one and underlaps another of such blades; a propelling shaft carrying the blades; and a circular rib of constantly increasing dimensions of projection on the thrust producing water resisting surfaces of each of such blades, to retard the flow of water over said surfaces; said blades being of spiral con-

formation of different lengths longitudinally of the shaft and having their starting points one leading the other and each conforming to a helix at a given point of equal 5 depth of the spiral screw in relation to each other as it recedes from said shaft; said blades each being of concave curvature, of slightly different depth, so that a given 10 mass of water is productive of equal thrust in each blade in an equal duration of time

and thereby produces equal propulsive effect, substantially as described.

In testimony whereof, I have hereunto signed my name to this specification in the presence of two subscribing witnesses.

GIUSEPPE GAYS.
